PUMP

Daniel R. Scholes, Oak Park, Ill., assignor to
Aermotor Company, Chicago, Ill., a corpora-
tion of Illinois

Application July 27, 1931, Serial No. 553,284

3 Claims. (Cl. 103—218)

This invention relates to pumps preferably for use in pumping from wells or the like. In devices of this nature it is oftentimes desirable to have the pumping mechanism so arranged as to operate a pump at or above the frost line, and at other times to operate a pump located below the frost line. In accordance with the present invention the power casing is so arranged that it may be connected with a pump located either above the frost line or below the same, and with the expenditure of very little time. A further object of the invention is to provide a pump operating means so arranged that it may be easily and quickly connected with the pump regardless of whether the latter be a surface pump or a deep well pump.

Another object of the invention is to provide a power head casing with lugs having both vertical and horizontal seats, to either of which pump supporting means may be secured as desired.

Other objects, advantages and capabilities will later more fully appear.

My invention further resides in the combination, construction and arrangement of parts illustrated in the accompanying drawings, and while I have shown therein a preferred embodiment I wish it to be understood that the same is susceptible of modification and change without departing from the spirit of my invention.

30 In the drawings:—

Fig. 1 is a front elevation of a pump mechanism embodying my invention, parts being broken away for the sake of convenience.

Fig. 2 is a side elevation of the pump mechanism shown in Fig. 1.

Fig. 3 is a fragmentary perspective view of the lower portion of the driving mechanism housing showing the attaching lugs with drop pipes secured thereto.

40 Fig. 4 is a view similar to Fig. 3 with the drop pipes and their securing means omitted, but showing the bolts in position for securing the pump head to the underneath horizontal faces or seats of the lugs.

45 Fig. 5 is a side elevation of the pumping mechanism embodying my invention, but showing the pump head secured directly to the horizontal seats of the attaching lugs without the use of drop pipes.

50 Fig. 6 is a fragmentary front elevation of the lower front portion of the driving mechanism housing, showing the pump head secured to the attaching lugs in the manner of Fig. 5.

55 Fig. 7 is an inverted perspective view showing the bottom portions of the attaching lugs and

adjacent portions of the driving mechanism housing.

Referring in detail to the drawings, the driving mechanism housing 1 may be of any type desired, but for convenience is shown as being of the type and construction disclosed in my co-pending application Ser. No. 509,740. As the specific construction of the driving mechanism housing, or power head and driving mechanism contained therein, forms no part of the present invention the same will not be described in detail, except to state that through the medium of suitable mechanism the connecting rods 2 are given a vertical reciprocation, which reciprocation is transmitted to the cross-head 3, secured to the connecting rods 2, the cross-head 3 carrying lug 4, to which is secured for reciprocation with cross-head 3 the upper end of a rod 5, operating in an air pump 6, used in a conventional manner in connection with the main pump.

When my invention is used for supporting a pump head below the frost line, as shown in Figs. 1 and 2, the air pump 6 is provided with suitable and appropriate means for cooperation with the pump in the well-known manner. The pump head 7 having the usual water chamber *a*, and other associated parts, is supported by drop pipes 8 and 9, which in turn are attached to the lugs 10 and 11, which lugs are preferably (though not necessarily) integral with the driving mechanism housing or power head 1, these lugs being formed as shown in Figs. 3 and 4 with arcuate seats or faces 12 and 13, and as shown in Fig. 7 with horizontal faces or seats 14 and 15.

When these lugs are to be used for attaching to the housing 1 a pump head to be positioned a substantial distance below the housing 1, drop pipes 8 and 9 will be seated in the arcuate seats 12 and 13, as shown, and tightly clamped therein by means of U-bolts 16 and 17, which U-bolts are tightened in place by means of nuts 18. Drop pipes 8 and 9 will be preferably hollow and of construction generally understood in the art, and carrying at their lower end the pump head 7, as shown in Figs. 1 and 2.

Depending from pump head 7 is the customary well pipe 19, within which operates the main pump rod 20, this pump rod being reciprocated by rod 21, which in turn is given a vertical reciprocation by cross-head 3, to which it is attached. In a manner well understood in the art cross-head 3 may be reciprocated either through the medium of the mechanism within the housing 1 or directly from a windmill by suitable connection therewith through rod 22, shown in Fig. 5. Also

secured to pump head 7 is the discharge pipe 23 and other appropriate parts.

When, however, it is desired to attach the pump head adjacent to the housing 1, the drop pipes 8 and 9 may be omitted and the pump head secured directly to the casing 1 by bringing the horizontal faces 24 of the pump head into seating engagement with the horizontal seats 14 and 15 of lugs 10 and 11, and securing the same there-
10 against by means of bolts 25. When thus connected the pump head includes the discharge head 26, the well pipe 27, the main pump rod 28, and cap 29, to which latter is connected the air pump 6. Also connected with the pump head is the usual packing tube 30, in which the pump rod 22 is connected with the main pump rod 28 of the pump.

All that is necessary to be done to disconnect the pump head shown in Fig. 5 from casing 1 is to remove bolts 25, and when such removal is effected and the pump head taken away the drop pipes 8 and 9 of a deep well pump, or other pump located below the frost line, may be quickly and readily positioned within the arcuate seats 12 and 13, and rigidly secured thereto by U-bolts 16 and 17.

It is thus seen that in the present invention I have provided means for selectively securing to the driving mechanism housing or power head 1 either an anti-freezing pump (pump head to be positioned below the frost line) or a pump in which the pump head is secured directly to the housing or power head 1, this change being effected with the expenditure of a minimum amount of time and labor. This greatly increases the field of usefulness of the power head by enabling it to be quickly and easily attached to the different types of pumps referred to, and also enables the quick and ready detachment of the pump from the power head for removal of the pump, or other purposes.

Having thus disclosed my invention, I claim:

1. In mechanism of the character described in combination, a driving mechanism housing, lugs

formed on said housing, said lugs having vertical arcuate seats and horizontal openings, a U-bolt extending through said openings, a drop-pipe seated in each of said arcuate seats and clamped therein by a U-bolt, said drop-pipes being adapted to support a pump head below the frost line, said lugs each also having a horizontal seat adapted to have a pump head secured thereto when it is desired to support the latter above the frost line, said lugs each also having a vertical opening adapted to receive a bolt for securing the pump head to the horizontal seat.

2. In mechanism of the character described in combination, a driving mechanism housing, a pair of lugs formed on said housing, said lugs each having a vertical seat and a horizontal opening with a bolt extending through said opening, a pump supporting part securely fastened against each of said vertical seats by said bolts to support a pump head below the frost line, said lugs each also having formed on its bottom portion a horizontal seat and a vertical opening, said horizontal seats being adapted to have a pump head secured thereto by a bolt passing through each of said vertical openings with the pump head positioned above the frost line.

3. In mechanism of the character described in combination, a driving mechanism housing, a pair of lugs formed on said housing, said lugs each having a vertical seat and a horizontal opening with a bolt extending through said opening, a pump supporting part securely fastened against each of said vertical seats by said bolts to support a pump head below the frost line, said lugs each also having formed on its bottom portion a horizontal seat and a vertical opening, said horizontal seats being adapted to have a pump head secured thereto by a bolt passing through each of said vertical openings with the pump head positioned above the frost line, said vertical seats and their respective bolts permitting vertical adjustment of said pump supporting parts.

DANIEL R. SCHOLES.
